DRAWBAR

Edward Rodemeyer, Hampton, Iowa

Application July 3, 1937, Serial No. 151,931

2 Claims. (Cl. 55—84)

This invention relates to draw bars, and more particularly to draw bars of the folding type and adapted for use in conjunction with harrows for hitching the harrows to a tractor or the like.

5 An object of the present invention is to provide an improved foldable draw bar which will be light in weight and can be readily folded so as to permit passage of the draw bar through a gate or the like.

10 A further object of the invention is to provide an improved connection between the center section and the end sections of the draw bar as will not only facilitate the folding of the end sections relative to the intermediate section of the draw bar but will also serve to shorten the turn of the draw bar while the same is being used for dragging the harrows over the field being worked upon.

15 The invention, together with its objects and advantages, will be best understood from a study 20 of the following description taken in connection with the accompanying drawings, wherein:

Figure 1 is a top plan view of the draw bar in extended position.

Figure 2 is a similar view of the draw bar, but 25 in a folded position.

Figure 3 is a plan view of the draw bar per se and illustrating the manner in which an end section of the draw bar operates when the same is negotiating a turn.

30 Figure 4 is a fragmentary edge elevational view of a portion of the intermediate section of the draw bar and one end section, showing the pivotal connection between said sections.

Figure 5 is an end elevational view of the intermediate section of the draw bar.

Figure 6 is a fragmentary elevational view illustrating a slightly modified form of end section.

Referring to the drawings by reference numerals, it will be seen that in the preferred embodiment thereof my improved draw bar comprises an intermediate section 5 and longitudinally tapering end sections 6—6.

At the respective opposite ends thereof the intermediate draw bar section 5 is bifurcated to 45 provide at each of said ends a pair of coextensive, apertured ears 7—7 between which the largest end of an end draw bar section 6 is accommodated and is pivoted through the medium of a rivet or other suitable pivot element 8.

50 Also, extending forwardly from the intermediate draw bar section 5 at each end thereof is a rigid arm 9 braced with respect to the draw bar section 5 through the medium of a diagonal brace 10.

55 Each arm 9 at the free end thereof has an-

chored thereto a suitable length of chain 11, the free end of which is adapted to be engaged with an eye 12 on the free end of a draw bar end section 6 in a manner to retain the draw bar end section 6 in longitudinal alignment with the intermediate draw bar section 5, at least to the extent of preventing rotative movement of an end draw bar section in a direction rearwardly with respect to the intermediate draw bar section 5.

As shown in Figure 3, the intermediate draw bar section 5 may be provided with a single hitch 13, or as suggested in Figure 1, with two, or as otherwise known as a double hitch 14—14.

At the rear edge thereof the intermediate draw bar section 5 is provided with a suitable arrangement of eye bolts 15, whereby two harrows 16 may be suitably coupled thereto.

The intermediate draw bar 5 at the ends thereof, and the end draw bar sections 6 have their free ends also provided with eye bolts 15a, whereby 20 endmost harrows 17 may be coupled thereto in a manner clearly shown in Figure 1.

As shown in Figure 2, when it is desired to fold the draw bar, as may be required when passage is to be made through a gateway or the like, chains 11 are disconnected from the end sections 6, while the harrows 17 are uncoupled from the eye bolts 15a on the intermediate draw bar section 5.

The draw bar sections 6 are then swung rearwardly to a position at right angles to the intermediate draw bar section 5 and the endmost harrows 17 are aligned with the intermediate harrows 16 and at their inner sides suitably coupled to the inner sides of the intermediate harrows 16, as clearly shown in Figure 2. Thus, the draw bar and harrow assembly is so laterally reduced as to permit passage of the same through a gateway or the like.

It will also be apparent that with this draw bar, when a turn is being negotiated, the draw bar sections are permitted to swing relative to one another, thus shortening the turn being made.

A salient feature of the present invention is 45 in having the end sections 6 of the draw bar swingable in a horizontal plane as distinguished from vertical swinging movement, since where the end sections swing vertically, as is now the case with known foldable draw bars, the end- 50 most harrows must be placed upon the intermediate harrows instead of arranged in alignment therewith, as is permitted where the end sections, in accordance with the present invention, are swingable on horizontal planes.

As shown in Figure 6, if desired, each end section, that end section in Figure 6 being indicated by the reference numeral 6a may be formed from a single length of strap iron folded upon itself intermediate the ends with the terminals 5 of the strap straddling one end of the intermediate section 5a and pivoted to the said end of the section 5a through the medium of a pivot bolt 8a.

10 It is thought that a clear understanding of the construction, utility and advantages of my draw bar will be had without a more detailed description.

Having thus described the invention, what is 15 claimed as new is:

1. A draw bar for harrows comprising an intermediate section and a pair of end sections, means pivotally connecting said end sections at one end thereof to the ends of said intermediate 20 section, whereby said end sections may be swung in either direction and in horizontal planes relative to said intermediate draw bar section, in combination with a plurality of harrows, and inter-engaging means on the harrows and on 25 the sections of the draw bar for coupling the

harrows to the draw bar sections and also for coupling the outermost harrows to the intermediate harrows and in alignment with the intermediate harrows when the end draw bar sections are folded rearwardly to a position substantially at right angles to the intermediate draw bar section. 5

2. A device of the class described comprising a draw-bar including an intermediate section and end sections hingedly connected to the ends 10 thereof for swinging movement at right angles thereto, intermediate harrows connected to the intermediate section, a pair of outer harrows, means connecting one side of said outer harrows to the free end portions of the end sections, and 15 inter-engaging means on the inner sides of said outer harrows and the end portions of the intermediate section for connecting the outer harrows thereto when the draw-bar sections are aligned and for connecting said outer harrows 20 to the inner harrows in longitudinal alignment therewith when the outer sections are at substantially right angles to the intermediate section.

EDWARD RODEMEYER. 25
